UNITED STATES PATENT OFFICE.

NIELS PIHL JENSEN, OF EPHRAIM, UTAH.

MUSIC-LEAF TURNER.

SPECIFICATION forming part of Letters Patent No. 774,521, dated November 8, 1904.

Application filed July 14, 1904. Serial No. 216,494. (No model.)

To all whom it may concern:

Be it known that I, NIELS PIHL JENSEN, a citizen of the United States, and a resident of Ephraim, in the county of Sanpete and State 5 of Utah, have invented a new and Improved Music-Leaf Turner, of which the following is a full, clear, and exact description.

The object of the invention is to provide a new and improved music-leaf turner for use 10 on pianos, organs, music-racks, and the like and arranged to permit of conveniently turning the leaves successively over in either direction to permit of operating the device either by hand or by foot, and in the latter case to 15 render the device especially serviceable for use on portable music-racks such as are used by band-musicians.

The invention consists of novel features and parts and combinations of the same, as will be 20 more fully described hereinafter and then pointed out in the claims.

A practical embodiment of the invention is represented in the accompanying drawings, forming a part of this specification, in which 25 similar characters of reference indicate corresponding parts in all the views.

Figure 1 is a perspective view of the improvement as applied to a portable music-rack. Fig. 2 is an enlarged plan view of the improvement, part of the casing-cover being broken out. Fig. 3 is a transverse section of the improvement on the line 3 3 of Fig. 2, and Fig. 4 is a sectional rear elevation of the same on the line 4 4 of Fig. 3.

35 The casing A, on which the music-leaf turner is mounted, is attached to a stand or other suitable support B, and the cover A' of the said casing is formed at its rear end with a rack A² for supporting a book or sheet-music, the 40 leaves of which are to be turned by the device.

In a suitable bearing arranged on the rear of the casing A is mounted to turn the vertically-disposed solid hub or pivot C' of a swing-arm C, disposed horizontally, and on 45 the said hub C' is mounted to turn the hub C² of a second swing-arm C³, and on the hub C² is mounted the hub C⁴ of a third swing-arm C⁵, the said hub C⁴ being also mounted to turn in a suitable bearing D, fixed to the under side 50 of the cover A' of the casing. (See Fig. 3.)

On each of the several swing-arms C, C³, and C⁵ is adjustably held a clamping device E for engaging the bottom portion of a leaf to be turned, as plainly indicated in Fig. 1.

On the hubs C', C², and C⁴ within the casing 55 A are secured gear-wheels F, F', and F², located one above the other and in mesh with segmental gear-wheels G, G', and G², mounted to swing on a common pivot G³, carried by the casing A. (See Fig. 3.) The webs of the 60 several segmental gear-wheels G, G', and G² are guided between guide-plates H, attached at their ends to posts H' and H², secured to the bottom of the casing A and forming stops for the said webs to limit the swinging motion of the segmental gear-wheels G, G', and 65 G² in either direction.

Each of the segmental gear-wheels G, G', and G² is provided at opposite sides of its fulcrum with integral toes G⁴ and G⁵, of which 70 the toes G⁴ for the segmental gear-wheels G, G', and G² are adapted to be successively engaged by the staggered heads of a pawl I, secured to a slide J, mounted to slide transversely in a suitable bearing K, arranged on 75 the casing A, and the toes G⁵ of the several segmental gear-wheels G, G', and G² are adapted to be engaged by the reversibly-staggered heads of a pawl I', secured on a slide J', likewise mounted to slide in the bearing 80 K, independent, however, of the slide J.

The slides J and J' are provided with depending integral members J², extending through slots in the bottom of the casing A, and the lower ends of the said members J² are 85 pivotally connected with the forked ends of levers L and L', provided at their forward ends with knobs or finger-pieces L² and L³ to enable the operator to press the knobs to impart the desired swinging motion to the corresponding lever L or L'. Now by pressing the knob L² or L³ a swinging motion is given to the corresponding lever L or L', so as to move the slide J or J' from a normal rearward position forwardly, and when the knob 95 is released a spring N or N', pressing on the lever, returns the lever, and with it the slide J or J', to its normal rearmost position. Instead of pressing the levers L and L' by hand, as described, they may be operated by the 100

foot of the musician, and for this purpose the levers L and L' are pivotally connected by links O and O' with pedals P and P' , fulcrumed on the lower portion of the stand B within convenient reach of the feet of the operator. When the slide J is moved from its rearward normal position into a forward position, then one of the heads of the pawl I engages a corresponding toe G^4 to impart a 10 swinging motion to the corresponding segmental gear-wheel G , G' , or G^2 to swing the same from the right to the left in the direction of the arrow a' , so as to turn the corresponding gear-wheel F , F' , or F^2 , and consequently swing the swing-arm C , C' , or C^5 from the right to the left to turn the corresponding leaf over in the same direction. When the lever L' is pressed and the slide J' is moved from a normal rearmost position to a forward 20 position, then one of the heads of the pawl I' engages the corresponding toe G^5 to swing the respective segmental gear-wheel G or G' from the left to the right in the inverse direction of the arrow a' to turn the gear-wheel F , F' , or F^2 in a reverse direction, so as to swing the arm C , C' , or C^5 from the left to the right to turn a leaf in a similar direction. Thus by the arrangement described a leaf may be turned in either direction—that is, from 30 the right to the left or from the left to the right—in case it is desired to repeat a passage from a previous page or when originally setting the device to turn the leaves over successively from the right to the left.

35 The book or sheet-music is held at its middle between the members Q' and Q^2 of a clamping device Q , preferably supported from the rack A^2 , the member Q^2 being fulcrumed at its lower end on the lower end of the member Q' , which in turn is provided at this end with a downwardly-extending pin Q^3 , engaging an opening in the rack A^2 , as plainly indicated in Fig. 3. The two members Q' and Q^2 are removably fastened together at the 45 upper end by a suitable sliding head Q^4 . (Indicated in Fig. 2.) By sliding the head Q^4 forward the member Q^2 can be swung open to allow of conveniently inserting or removing the book or sheet-music between or from the 50 members, it being understood that the head serves to hold the members in a closed position after the book is inserted or removed therefrom.

55 The operation is as follows: After the book or sheet-music is placed in position on the rack A^2 and clamping device Q then successive leaves are engaged with the clamping devices E of the several arms C , C' , and C^5 , and the said arms are swung over to the right by 60 repeatedly pressing the lever L' . The several segmental gear-wheels G , G' , and G^2 now stand in a right-hand position, with the toe G^4 of the segmental gear-wheel G in engagement with its head of the pawl I and the other 65 heads for the toes G^4 of the segmental gear-

wheels G' and G^2 out of alinement, so that when the operator presses the lever L and the slide J and pawl I move forward then the head in engagement with the toe G^4 of the segmental gear-wheel G imparts a turning motion to the gear-wheel F to turn the hub C' and its arm C to swing the same from the right to the left to turn the first page over. As soon as the operator releases the lever L the latter is returned to its previous position 70 by the spring N , and by the pawl I moving rearward to its normal position the next head of the pawl I engages the toe G^4 for the segmental gear-wheel G' , while the toe G^4 for the segmental gear-wheel G^2 is out of engagement with its head on the pawl I , and consequently when the musician has finished the next pages and presses the lever L then a swinging motion is given by the pawl I to the segmental gear-wheel G' , which turns the 75 gear-wheel F' to swing the arm C^5 from the right to the left and with it the leaf carried by this arm. When the operator releases the lever L and the slide J and pawl I return to a rearmost position, then the top head of the pawl I engages the remaining toe G^4 (see Fig. 2) of the top segmental gear-wheel G^2 , and when the operator now presses the lever L then this segmental gear-wheel G^2 is caused to swing to turn the gear-wheel F^2 to swing the arm C^5 80 from the right to the left and with it the last leaf. Whenever it is desired to swing one of the leaves back from the left to the right for repeating a passage of music, then the operator 85 presses the lever L' , so that the slide J' and pawl I' move from a rearmost position 90 forwardly, and the corresponding head of the pawl I' engages the corresponding toe G^5 , so as to impart a return swinging motion to the respective segmental gear-wheel G , G' , or G^2 95 to swing the arm C , C' or C^5 back from the left to the right and with it the corresponding leaf. Thus the operator at will can swing a 100 leaf from the right to the left or swing this leaf back again for repeating a passage of music or for other purposes. The operator instead of manipulating the levers L and L' or the pedals P and P' can at any time take hold 105 of the leaves and turn the same by hand, especially when it is desired to look over a piece 110 of music before playing, it being understood that the swing-arms and their gears are unlocked in both positions to allow convenient 115 turning over of the leaves by hand.

120 It is understood that although I have shown the device provided with but three swing-arms and connected gear it is evident that less or more such swing-arms may be employed to turn fewer or more leaves, and hence I do not limit myself to the particular number of swing-arms and their operating mechanism described, as the same may be varied.

125 Having thus described my invention, I claim as new and desire to secure by Letters Patent—
1. A music-leaf turner comprising a plu- 130

rality of swing-arms having coinciding axes and means for engaging the leaves to be turned, gear-wheels secured on the hubs of the swing-arms, segmental gear-wheels having coinciding axes and in mesh with the said gear-wheels, each segmental gear-wheel being provided with toes on opposite sides of its fulcrum, and manually-controlled pawls, one for engaging the toes located on one side of the segmental gear-wheels and the other pawl for successively engaging the toes on the other side of the segmental gear-wheels.

2. A music-leaf turner comprising a plurality of swing-arms having coinciding axes and means for engaging the leaves to be turned, gear-wheels on the hubs of said swing-arms, segmental gear-wheels having coinciding axes and in mesh with the said gear-wheels, each segmental gear-wheel being provided with toes on opposite sides of its fulcrum, manually-controlled slides, and pawls moving with the said slides and each having staggered heads, the heads of one pawl being adapted to successively engage the toes located on one side of the segmental gear-wheels and the staggered heads of the other pawl being adapted to successively engage the toes on the other side of the segmental gear-wheels.

3. A music-leaf turner comprising a plurality of swing-arms having coinciding axes and means for engaging the leaves to be turned,

gear-wheels on the hubs of said swing-arms, segmental gear-wheels having coinciding axes and in mesh with the said gear-wheels, each segmental gear-wheel being provided with toes on opposite sides of its fulcrum, slides, pawls moving with the said slides and each having staggered heads, the heads of one pawl being adapted to successively engage the toes located on one side of the segmental gear-wheels and the staggered heads on the other pawl being adapted to successively engage the toes on the other side of the segmental gear-wheels, and spring-pressed levers under the control of the operator and connected with the said slides.

4. A music-leaf turner provided with a swing-arm having means for engaging the leaf to be turned, a gear-wheel secured on the hub of the said swing-arm, a segmental gear-wheel in mesh with the said gear-wheel and provided with toes on opposite sides of its fulcrum, and pawls for engaging the said toes, to swing the segmental gear-wheel in either direction.

In testimony whereof I have signed my name to this specification in the presence of two subscribing witnesses.
